UNITED STATES PATENT OFFICE.

CHARLES ORSEMEUS COWAN, OF SEATTLE, WASHINGTON.

DRINKING FOUNTAIN.

1,409,930.

Specification of Letters Patent. Patented Mar. 21, 1922.

Application filed December 8, 1920. Serial No. 429,124.

To all whom it may concern:

Be it known that I, CHARLES ORSEMEUS COWAN, a citizen of the United States, and a resident of Seattle, in the county of King and State of Washington, have invented certain new and useful Improvements in Drinking Fountains, of which the following is a specification.

My invention relates to drinking fountains, and a purpose of my invention is the provision of a drinking fountain of simple and efficient construction which is readily attachable to or detachable from a faucet of the ordinary construction.

It is also a purpose of my invention to provide a drinking fountain which is adjustable to allow for different water pressures whereby, the proper flow of water through the fountain is insured irrespective of the water pressure. Furthermore, my invention provides means for deflecting the water within the fountain so as to create a rolling action of the stream and to thus allow the ready drinking of water from the fountain.

I will describe one form of fountain embodying my invention and will then point out the novel features thereof in claims.

In the accompanying drawings:

Figure 1 is a view showing in side elevation one form of fountain embodying my invention.

Figure 2 is a view similar to Figure 1 with portions of the fountain in vertical section.

Figures 3, 4 and 5 are transverse sectional views taken on the lines 3—3, 4—4 and 5—5, respectively, and looking in the direction of the arrows.

Similar reference characters refer to similar parts in each of the several views.

Referring specifically to the drawings and particularly to Figures 1 and 2, my invention in its present embodiment comprises a substantially U-shaped length of pipe P, one arm of which is provided with a union N preferably formed of rubber or other flexible material and having its lower end constricted to tightly embrace the upper end of the pipe P. The upper end of the union N is of greater diameter than the lower end and is adapted to receive the faucets (not shown) and to so embrace the same as to support the fountain as a unit upon the faucets, it being understood that the union provides a water-tight joint between the faucet and pipe P. The free extremity of the other arm of

the pipe P is screw threaded exteriorly to adjustably receive the head of the fountain. The fountain head comprises in the present instance a casing 15 of the contour shown in Figures 1 and 2, and suitably secured within the casing are discs or plates 16 and 17. The disc 17 is arranged in superposed relation with respect to the disc 16 and is provided axially thereof with an opening 17^a through which the water from the pipe P is adapted to pass as will be more fully described hereinafter. The disc 16 is provided axially thereof with an opening, the walls of which are screw-threaded to engage the adjacent end of the pipe P, the disc being further provided with a plurality of perforations 16^a as clearly shown in Figure 3 through which the waste water from the fountain is discharged. The disc 16 can be locked in any adjusted position upon the pipe P by means of a lock nut 18 which, as shown in Figure 2, engages the under side of the disc 16 so as to prevent accidental rotation of the disc. By means of this adjustment, it will be clear that the vertical position of the fountain head as a unit can be varied so as to vary the distance between the end of the pipe P and the disc 17.

Within the casing 15 and normally resting upon the disc 17 is a deflecting plate 19 provided on its under side with lugs 19^a which constitute feet for supporting the plate in spaced relation to the disc 17. As shown in Figure 5, the plate 19 in the present instance is of disc formation and is provided with three lugs 19^a. The casing 15 is of substantially frusto-conical formation, its upper end being formed with a drinking opening 20, the wall of which is downturned to provide a deflecting lip 20^a that is adapted to coact with the plate 19 in controlling the flow of water within the fountain head.

In the operation of the fountain, the pipe P is secured to a faucet of standard form through the medium of the union N so that the fountain head is supported in vertical position as shown in Figures 1 and 2. The water discharged from the threaded end of the pipe P impinges upon the under side of the plate 17, a portion of the water passing through the restricted opening 17^a where it engages and lifts the deflecting plate 19. Under the action of the deflecting plate 19, the water is forced to pass to the periphery of the plate and thence upwardly along the wall of the casing to the lip 20^a. The lip

20^a being bent downwardly causes the water to be directed downwardly thus imparting a rolling action to the flow of water within the opening 20. Such movement of the 5 water prevents its emission upwardly from the casing so that one in safety may drink from the opening 20. That water which is not discharged through the opening 17^a is deflected downwardly by the plate 17 where 10 it exits from the fountain head through the several perforations 16^a.

Should the pressure of water be excessive so that the deflecting plate 19 is thrown 15 against the lip 20^a so as to close the opening 20 and thus prevent the proper operation of the fountain, the fountain head is adjusted by a turning of the nut 18 to a disengaging position with respect to the disc 16 thereby permitting rotation of the head upon 20 the pipe P so as to move the plate 17 a greater distance from the discharge end of the pipe P and to thereby lessen the force of the water passing through the opening 17^a. On the other hand should the pressure of water 25 be insufficient to discharge the necessary amount of water through the opening 17^a to produce the desired flow within the opening 20, the fountain head can be adjusted downwardly upon the plate P so as to move 30 the discharge end of the pipe in closer proximity to the plate 17. This obviously increases the amount of water passing through the opening 17^a and impinging upon the plate 19.

35 Although I have herein shown and described only one form of drinking fountain embodying my invention, it is to be understood that various changes and modifications may be made herein without departing from 40 the spirit of the invention and the spirit and scope of the appended claims.

What I claim is:

1. A drinking fountain comprising, a pipe, 45 a fountain head supported on the upper end of the pipe and including a casing formed at its upper end with a drinking opening, the wall of which is bent downwardly to provide an inturned lip, a plate secured within the casing adjacent its base and formed with

discharge perforations, an opening formed 50 axially in the plate and having the walls thereof threaded to engage said pipe, a nut threaded on the pipe and engageable with said plate for locking the plate against rotation in one direction, a second plate within 55 the casing and arranged in spanning relation with respect to the end of said pipe, a discharge opening formed axially in the second plate and registering with the upper end 60 of said pipe, a deflecting plate resting on the second plate and spanning said discharge opening, and lugs formed on the deflecting plate for normally spacing said plate from the second plate.

2. A drinking fountain comprising, a pipe, 65 a perforated plate threadedly engaging the upper end of the pipe, means for locking the plate in adjusted position, a casing secured to the plate, the upper end of said casing being formed with a drinking opening, the wall 70 of which is downturned to provide a depending lip, a second plate fixed within the casing at a point above the upper end of said pipe, a discharge opening formed in the second plate directly above the upper end of 75 said pipe, and means between said drinking opening and the second plate adapted to cause the water passing upwardly through the discharge opening to spread and impinge 80 upon the inner side of said lip for the purpose described.

3. A drinking fountain comprising, a pipe, 85 a fountain head supported on one end of the pipe and including a disc threadedly engaging the pipe and formed with perforations, a tubular casing embracing the disc, a second disc above the adjacent end of the pipe, a discharge opening formed in the second disc, and disposed directly above the adjacent end of the pipe, a deflecting plate resting 90 on the second plate and spanning said discharge opening, and a circular depending lip formed on the upper end of the casing and adapted to coact with said deflecting plate for directing water in a predetermined 95 path within the casing.

CHARLES ORSEMEUS COWAN.
